COKE OVEN DOOR ASSEMBLY

Charles V. McIntire, Short Hills, N. J., assignor
to Semet-Solvay Engineering Corporation, New
York, N. Y., a corporation of New York

Application June 2, 1931, Serial No. 541,557

3 Claims. (Cl. 202—248)

This invention relates to by-product coke ovens, and more particularly, to the structure of the sides of the battery; i. e., the arrangement of the brickwork at the ends of the heating walls and coking chambers and the construction of the closures for the opposite ends of the coking chambers.

One object of this invention is to provide a durable and efficient construction and arrangement of brickwork for the ends of the heating walls and coking chambers such that a gas-tight joint between the sides or liner brick and the end brick is provided and leakage of gas from the end flues into the coking chambers or atmosphere is prevented.

Another object is to provide armour or flash plates for the brickwork, both the armour and the brickwork being of relatively simple and compact design. In accordance with this invention, the flash plate functions to protect the brickwork and cooperates with the doors removably positioned in the openings at the ends of the coking chambers to seal the coking chambers during coking. Further, the flash plates are designed so that a maximum area of their surfaces is exposed to the atmosphere and a minimum portion thereof extends beyond the clay or luting seal. Hence, the flash plates are maintained at a temperature sufficiently low to prevent warping thereof. The use of a number of flash plates for covering the ends of the heating walls, the flash plates being disposed with expansion joints or spaces therebetween permits expansion and contraction of the plates with changes in temperature occurring during charging, coking and pushing operations and eliminates warpage and cracking which are liable to occur when long steel bars or plates are used for armouring the sides of coke oven batteries.

Still a further object of this invention is to provide a coke oven door closure, the door of which, when in closed position, has a minimum area of its surface extending beyond the clay joint or luting seal so that a minimum portion thereof is subjected to the action of the high temperature gases within the coking chamber. Hence, the area of the door surface which of necessity must be cleaned of the deposits accruing thereon during the coking operation is materially reduced and less time and labor are consumed in cleaning the doors.

This invention comprehends an arrangement of brickwork for the ends of the flued heating walls defining the sides of the coking chambers involving end or intermediate bricks disposed between

projections on side or liner bricks. The side or liner bricks are held in gas-tight engagement with the intermediate or end bricks by jamb bricks constructed and arranged to engage the extensions or projections on the side bricks and force them into contact with the end or intermediate bricks. Armour or flash plates extend about the exterior surface of the jamb bricks and are shaped to provide flanges which cooperate with the sides of the coke oven door to form luting recesses. The door of this invention is disposed so that a minimum portion thereof extends beyond the luting seal into the coking chamber space, and consequently, only a minimum portion is subjected to conditions within the coking chamber, and the area of the door surface which must be cleaned from the deposits accruing thereon during coking is materially reduced.

In the accompanying drawings forming a part of this specification and showing, for purposes of exemplification, a preferred form and manner in which the invention may be embodied and practiced, without limiting the claimed invention to such illustrative instance,

Fig. 1 is a fragmentary vertical section, taken on the line 1—1 of Fig. 2, through a coking chamber of a by-product coke oven battery, illustrating a door for an open end of the coking chamber;

Fig. 2 is a fragmentary side elevation of one side of a coke oven battery. Since the other side of the battery is of like construction and design, it is considered unnecessary to show both sides and the description herein will be confined to the one side of the battery shown on the drawings;

Fig. 3 is a fragmentary horizontal section taken on the line 3—3 of Fig. 2 through two heating walls and an intervening coking chamber; and

Fig. 4 is a fragmentary vertical section through the ends of the heating walls taken in a vertical plane passing through the line 4—4 of Fig. 3 and showing the staggered arrangement of bricks in the ends of the heating walls, the doors closing the ends of the coking chambers being omitted from this figure for the sake of clarity.

Referring to the drawings, reference numeral 11 designates a horizontally elongated coking chamber of a coke oven battery. As customary, the battery is composed of alternating coking chambers 11 and heating walls 12, arranged side by side in a row with crosswise extending regenerators (not shown) positioned beneath the coking chambers, parallel thereto. The regenerators communicate with the flues in the heating walls above. Each coking chamber is defined by a pair

of heating walls 12 on opposite sides thereof, floor 14, and roof 15.

The open ends of each coking chamber are provided with closure members or doors 16 which are arranged to seal the ends of the coking chambers. Each door 16 comprises a channel-shaped frame 17, having at the top portion thereof a pair of flanges 18 and 19, at the lower portion a flange 21, and at opposite sides, extensions or flanges 29, the function of which will be herein-after described. The interior of the channel frame 17 is provided with alternate extending long and short transverse ribs 22 and 23 respectively, and longitudinal ribs 13 which serve to reinforce a lining 24 of refractory material. Lining 24 is formed with a protuberant portion 26 which projects within the coking chamber and an enlarged rear portion 27 contained within the channel-shaped frame 17. Recesses 28 are disposed in the opposite sides of the lining 24. The side flanges 29 of the door frame extend into the recesses 28 to hold the refractory lining 24 in position in the channel-shaped frame 17. Preferably, the lining 24 is composed of refractory bricks or tile, held together by any suitable bonding material and supported and reinforced by the inwardly, transversely extending ribs 22 and 23 and the longitudinally extending ribs 13. The lining abuts against the ribs 13 and 23, the space between the door frame and the lining being filled with a suitable heat insulating material, indicated by reference numeral 9.

Steel plates 31 are disposed on opposite sides in flat contact with the sides of the door, each plate extending the full length of the door and projecting a short distance beyond the line of contact between the flange 29 and the side of the door frame as shown in Fig. 3. Plates 31 are suitably fastened to the metal frame of the door, as for example by riveting. In order to retain the door 16 in closed position to seal the ends of the coking chambers, locking bars 33, slideable in guide members 35, integral with the frame 17 may be used. The ends of the locking bars engage inclined latches 34 mounted on the buckstays 71. A recess or hook 36 is formed on the frame 17 to accommodate the extracting hook of the door removing machine commonly employed for this purpose.

50 The heating walls 12 are composed of vertical combustion flues 39, the intermediate flues being defined by side bricks 37 and bricks 38 arranged at right angles to the side bricks and having one end rectangular, as indicated at 42, and the other end tapered, as indicated at 43, and provided with a shoulder 50. One end of each brick 37 is formed with notch 41, which cooperates with a like notch in the end of an adjacent brick to define a rectangular recess arranged to snugly receive the rectangular end of brick 38. The other end of each brick 37 is formed with an oblique face portion 43 and a notch 44 which cooperates with a like face portion on the end of a like brick 37 to form a seat for the tapered and shouldered end of brick 38. The bricks 37 and 38 are arranged as above described with the tapered ends of adjacent bricks 38 facing in opposite directions and with either the tapered or rectangular ends of the bricks 38 in longitudinal alignment 60 in adjacent heating walls facing towards each other as shown in Fig. 3.

In accordance with this invention, side or liner bricks 46 and 47 define the sides of the end vertical flues in each heating wall. One end of brick 75 46 is formed with a notch 49 similar to the notch

41 provided in brick 37 and the opposite end is formed with an inwardly extending projection or flange 51 having a stepped shoulder 52 and a rear face 53, consisting of an arcuate-shaped portion 54 and a plane portion 55. The exterior surface of brick 51 adjacent the end thereof is inclined as indicated at 56 to permit the ready entrance of door 16 into the coking chamber space defined by an adjacent pair of heating walls. The other liner brick 47 is provided with an inwardly extending flange or projection 57, the end of which is formed with a stepped shoulder 58. The rear surface of the extension or projection 57 consists of a plane portion 61 and an arcuate or convex portion 62 similar to the corresponding portions of brick 46 with the exception that extension 57 of brick 47 is of greater extent than the projection 51 of brick 46.

An end or intermediate brick 48, designed to closely fit within the space defined by the ends of the extensions 51 and 57, is formed with opposite stepped shoulders 63 complementary to the shoulders 52 and 58. The rear surface of the intermediate brick 48 is arcuate or convex-shaped so that it forms a continuation of the convex portions 54 and 62 of bricks 46 and 47 respectively. A jamb brick 65 has the contacting surface thereof formed with an arc-shaped or concave portion 66 complementary to the arc formed by the convex portions of bricks 46, 47 and 48, and has the end portions of the rear surface contiguous to the concave portion defined by vertical plane 67. Concave portion 66 of the jamb brick is arranged to engage the convex portions of bricks 46, 47 and 48 and the plane portion 67 of the jamb brick engages the plane surfaces 55 and 61 of the side bricks 46 and 47 respectively.

Due to this engagement between the concave portion of the jamb brick and the convex portions of the side or liner brick and the intermediate brick, the jamb brick functions to directly hold the side or liner brick 46 and 47 in binding engagement with the end brick 48, preventing separation of the liner brick from the end brick.

Bricks 46, 47, and 48 and the jamb brick 65 are laid vertically in courses which define the end structure of the heating walls, each side of each end of the heating wall being formed by 50 alternating bricks 46 and 47, disposed directly opposite each other to define the opposite sides of each heating wall. In view of the complementary structure of the ends of the projections of bricks 46 and 47, irrespective of which brick is to the right or left of the heating wall, the intermediate or end brick 48 fits properly between the projections 51 and 57 on the side or liner brick 46 and 47. Further, due to the fact that projections 57 on brick 47 are greater in 60 length than projection 51 on brick 46, alternating bricks 46 and 47 in each side of each heating wall will result in a horizontal staggering of the joints vertically of the heating wall between the side brick 46 and 47 and the intermediate brick 65 48 as shown in Fig. 4.

Flash or armour plates 68 of channel shape are disposed to cover the plane, rear and side surfaces of jamb brick 65. Each flash plate is formed with outwardly extending flanges 69 at 70 the side edges thereof. A number of flash plates 68 are used to armour the ends of the heating walls, the plates being preferably arranged with small spaces therebetween, which permits expansion of the metal plates with changes in tem- 75

perature and eliminates warping and cracking which occurs when a one-piece metal armour plate is utilized to cover the ends of the heating walls. The flash plates are held in place by buckstays 71, disposed at opposite sides of the battery and arranged to contact with the rear surface of the plates.

The doors 16, when in closed position, rest on a metal supporting plate 72 (Fig. 1), provided at the base of each coking chamber, the top of this plate lying flush with base 14 of the chamber. Flange 21 of the door frame is inclined so that it cooperates with the metal plate 72 to provide a luting space or recess. Flange 19 at the top of the door frame serves to partially cover the top portion of the refractory lining 24. The other top flange 18 is arranged to contact with the lintel plate 73. Flange 18 engages lintel plate 73 to form a luting recess for the top of the door. As hereinafter described, side plates 31 cooperate with flanges 69 on the flash plate to form luting recesses for the sides of the door. Hence, in accordance with this invention, the door may be luted on all four sides to provide a gas-tight closure for the ends of the coking chambers.

From the above description, it will be noted that the brick assembly constituting the ends of the flued heating wall structure is of simple and compact design. The assembly of bricks 46, 47 and 48 in gas-tight engagement is maintained by the jamb brick 65 which engages the rear surfaces of the extensions on the side or liner bricks 46 and 47 and the rear surface of the end brick 48 and holds the side or liner brick in engagement with the end brick. The jamb brick is protected and armoured by the flash plate 68, the flanges 69 of which cooperate with the side plates 31 on the door to provide a luting or sealing space for the door.

It will be further noted that the construction of the brickwork, flash plates, and door is such that substantially the entire surface of the metal flash plates and the metal door frame are exposed to the atmosphere and only a minimum extent of the flanges 69 of the flash plates and the side portions of the door frame extend beyond the luting seal where they are subjected to the high temperatures prevailing in the coking chambers. In view thereof, and further, due to the feature of having a plurality of flash plates armouring each end of each heating wall, the flash plates being arranged in spaced relation to permit contraction and expansion thereof with changes in temperature, warpage and cracking of the flash plates and metal work in the sides of the battery are eliminated. Also, in accordance with this invention, the major portion of the door does not extend into a coking chamber space beyond the luting seal, i. e. where the plates on the sides of the door contact with the flanges on the flash plates, so that carbonaceous substances are not deposited on the major portion of the door, but can form only on the minor portion exposed to conditions within the coking chamber. Hence, the area of the door surface which must of necessity be cleaned of the deposit accruing thereon during the coking operations is materially reduced and a saving in time and labor in the cleaning of the door is effected.

The invention, as hereinabove set forth, is embodied in a particular form of construction, but it is to be understood that it may be variously embodied within the scope of the following claims.

I claim:

1. A coke oven comprising a coking chamber, a pair of flued heating walls therefor flanking the coking chamber, one end of each heating wall being defined by side bricks disposed in pairs, each side brick having an extension at one end thereof and at substantially right angles thereto, the extensions of a pair of side bricks being disposed towards each other, the side of each of said extensions defining the end of the heating wall having a projecting portion thereon, an intermediate brick between the extensions of each pair of side bricks, said intermediate brick having a projecting portion on the side thereof defining the end of the heating wall, the intermediate bricks and the extensions of the side bricks of each end of each heating wall defining a wall of a flue in the heating wall with the projections on the extensions of the side bricks and on the intermediate bricks disposed in contiguous relation to produce a projecting portion of generally convex shape on the end of the heating wall, all the side bricks defining said flue having said extensions and a jamb brick having a portion of generally concave shape arranged to engage said convex projecting portion on the extensions of each pair of side bricks and on the intermediate brick to hold the side bricks in engagement with the intermediate brick.

2. A coke oven comprising a coking chamber, a pair of vertically flued heating walls therefor flanking the coking chamber, one end of each heating wall being defined by side bricks disposed in pairs, each side brick having an extension at one end thereof and at substantially right angles thereto, the extensions of each pair of side bricks being disposed towards each other, the side of each of said extensions defining the end of the heating wall having an arcuately shaped projecting portion thereon, an intermediate brick between the extensions of each pair of side bricks, said intermediate brick having an arcuately shaped portion on the side thereof defining the end of the heating wall, the radii of curvature of the arcuately shaped portions of each pair of side bricks and the intermediate brick being substantially the same, the intermediate bricks and the extensions of the side bricks of each end of each heating wall defining a wall of a vertical flue in the heating wall with the arcuately shaped portions thereon disposed exteriorly of said flue and in contiguous relation to produce a convex projecting portion on the end of the heating wall, all the side bricks defining said vertical flue having said extensions, and a jamb brick having a concave portion arranged to engage said convex projecting portion of each pair of side bricks and of the intermediate brick to hold the side bricks in engagement with the intermediate brick.

3. A coke oven comprising a coking chamber, a pair of vertically flued heating walls therefor flanking the coking chamber, one end of each heating wall being defined by side bricks disposed in pairs, each side brick having an extension at one end thereof and at substantially right angles thereto, the extensions of each pair of side bricks being disposed towards each other, the side of each of said extensions defining the end of the heating wall having an arcuately shaped projecting portion thereon, an intermediate brick between the extensions of each pair of side bricks, said intermediate brick having an arcuately shaped portion on the side thereof defining the end of the heating wall, the radii of curvature

of the arcuately shaped portions of each pair of side bricks and the intermediate brick being substantially the same, the intermediate bricks and the extensions of the side bricks of each end 5 of each heating wall defining a wall of a vertical flue in the heating wall with the arcuately shaped portions thereon disposed exteriorly of said flue and in contiguous relation to produce a convex projecting portion on the end of the heating wall, 10 all the side bricks defining said vertical flue having said extensions, a jamb brick having a

concave portion arranged to engage said convex projecting portion of each pair of side bricks and of the intermediate brick to hold the side bricks in engagement with the intermediate brick, flash plates embracing the jamb bricks and having flanges at the side edges thereof, and a door for the open end of the coking chamber provided with a portion arranged to make edge contact with the flanges on the flash plates. 5

10.

CHARLES V. MCINTIRE.
